MERLIN C. HAZARD, OF HUNTINGTON BEACH, CALIFORNIA, ASSIGNOR, BY DIRECT AND MESNE ASSIGNMENTS, TO MARVEL OIL TOOL COMPANY, OF HUNTINGTON BEACH, CALIFORNIA, A CORPORATION.

ROTARY UNDERREAMER.

Application filed October 13, 1923. Serial No. 668,306.

This invention relates to underreamers for use in enlarging the diameter of a well hole, and refers particularly to an underreamer for use in the rotary system of drilling or 5 constructing oil-wells.

Heretofore, some of the rotary underreamers which have been employed for enlarging a well hole below a well casing have had a decided tendency to lock the cutters 10 employed in the underreamers in the reaming or cutting position where the underreamer cannot be withdrawn through the well casing. Moreover, these prior underreamers have had a tendency to twist or 15 work by hard strata or rock in the well hole with the result that a portion of the well hole is not properly reamed to the enlarged diameter and an abutment is left in the well hole which will catch and obstruct the lowering of the well casing. Furthermore, in 20 the underreaming operation the heavy non-pulverized material scraped off the sides of the well hole tends to fall to the bottom of the hole, where it accumulates 25 and is not properly removed by the flushing fluid sent down to the underreamer, with the result that this material accumulates in the bottom of the well hole and obstructs the lowering of the underreamer, so that it 30 is necessary to remove the underreamer and insert in place thereof a boring tool to cut and mix up such heavy material and remove the same from the well. Furthermore, some of the underreamers employed in the 35 rotary system of drilling wells have a decided tendency to produce a crooked hole.

One object of this invention is to provide a form of underreamer which may be employed in the rotary system of reaming or 40 enlarging the bore of a well hole below a well casing, which underreamer is so constructed that the cutters may be readily collapsed to the non-reaming position at any time so that the underreamer may be withdrawn through the well casing. I have 45 found that by so constructing the underreamer, that in the cutting or reaming position only the cutting blades of the cutters extend beyond the body of the underreamer,

the cutters may more readily be translated 50 to the non-reaming position. This is due to the elimination of zones between the cutters or cutters and body where the débris or mud encountered in the reaming operation may pack or clog and tend to lock the 55 cutters in the reaming position. I have further found that by enclosing the mechanism, which in the underreamer is employed for translating the cutters to or from the reaming position, in a chamber substantially 60 sealed or closed off from communication either with the flushing mud sent down to the reamer or with the mud and débris in the well hole, the tendency of such mechanism to become locked in the reaming position 65 during the operation of the underreamer can be eliminated.

Another object of this invention is to provide an under reamer which will positively ream or enlarge all the bore of the well hole 70 without forming any shoulders or abutments in the well hole which may later obstruct the lowering of a well casing. This is accomplished by so constructing the cutters that throughout the reaming operation an 75 elongated vertical cutting edge is presented to the formation, which cutting edge is of such length that the underreamer cannot twist or work by the hard strata encountered in reaming the well, but such hard 80 strata will be repeatedly acted upon by the cutters of the underreamer throughout a relatively long period, thus insuring that such hard strata will be completely cut or sheared from the well hole. 85

Various other objects and advantages of this invention will be apparent from a description of the preferred embodiment or method of embodiment of the invention, and will be presented through the practice and 90 use of the invention.

In the accompanying drawings I have illustrated one example of an underreamer embodying the invention, in which:

Figure 1 is an elevation of an underreamer embodying the invention;

Figure 2 is an elevation at right angles to Fig. 1;

Figure 3 is an enlarged elevation mainly in longitudinal section with the underreamer in the position shown in Fig. 2;

Figure 4 is a transverse section on the line 4-4 of Fig. 3;

Figure 5 is a transverse section on the line 5-5 of Fig. 3;

Figure 6 is a transverse section on the line 6-6 of Fig. 3; and

10 Figure 7 is a perspective of one of the cutters employed in the underreamer.

Referring to the drawings; the underreamer comprises a body 1 having a threaded stem 2 at the top. From the lower end of the body extends a mixing and centering blade 3 which preferably terminates in fish-tail cutting edges 4. The blade 3 and the width of the cutting edges 4 is equal to the diameter of the body 1 of the underreamer. On opposed sides of the body 1 are formed cutter-ways 6 which extend from the lower end of the body upwardly in a direction longitudinal with the body to within a short distance of the threaded stem 2. The ways 6 are provided with cutter blade openings 5 extending longitudinal to the body, and said cutter blade openings 5 are preferably arranged at right angles to the cutting edges 4 of the blade 3. The ways 6 are enlarged inwardly from the openings 5 or dove-tailed in cross-section and receive cutters 7 which are provided with beveled shoulders 8 fitting the dovetailed section of the cutter-ways in one position. Throughout substantially the entire length of the cutters a cutting blade 9 extends which is shaped to pass through the openings 5 of the ways 6 and extend beyond the body 1 of the reamer. The body of the cutters 7 is of a length substantially equal to the length of the cutter-ways 6 of the body 1 so that in the reaming position said ways substantially enclose all parts of the body excepting the blade 9 of the cutters, and thus mud and débris cannot pack between the two cutters or in any zone between the body 1 and cutters 7. To impart the lateral movement to the cutters 7 which is essential to move the cutters to or from the underreaming position, rider surfaces 10 are formed on confronting surfaces of the body 1 and cutters 7. In this embodiment of the invention one of said rider surfaces is formed at the upper end of each cutter-way 6 and within the bottom of the way 6, said rider surface having a vertical, straight section 11 joining a downwardly and inwardly beveled section 12 at the bottom of the rider surface. The upper rider surface 10 extends outwardly in the bottom of the way 6 a sufficient distance so that, when the cutters 7 are translated over the rider surface, said cutters are held pressed against the contracting sections of the ways 6 and the straight section 11 of the rider surface 10, thus rigidly holding the cutter over the rider surfaces 10 the cutter blades 9 are moved parallel to their vertical cutting edge and the cutting edge is thus positioned always substantially vertically in the underreamer. In the underreamer the length of the cutter 7 may be as great as found necessary for the reaming operation, and this construction of the cutters and body permits ready changes in the length of the cutter by simply varying the length of the ways 6 and cutters 7 and where necessary the length of the body 1. To properly ream the well hole, the cutters 7 should be provided with a straight vertical cutting edge 15 of a length greater than the diameter of the body 1, and said straight edge 15 should terminate in an inwardly beveled or curving edge 16 which curves in a sufficient distance so that when the cutters 7 are in the reaming position the lower ends of the curved section 16 of the cutting edge are spaced apart a distance equal to or less than the radius of the well hole drilled by the fish-tail cutters 4. By this construction, the underreamer will be guided into the well hole formed by the fish-tail cutters 4 and the long, straight or vertical edge 15 of the cutters will repeatedly contact with the well hole, enlarging the same and straightening the well hole. Engaging the lower ends of both cutters 7 is provided a head 17 which works in a slot 18 in the cutter blade 3. Said head 17 is fixed to a rod 19 which extends axially upward through the body 1 of the underreamer fitting relatively closely the lower end of the body. Extending from the upward end of the body is provided a spring enclosing chamber 20 in which is placed a coil-spring 21 enclosing the rod 19 and seated at the bottom of the spring enclosing chamber 20 at one end and pressing against a nut or head 22 fixed to the upper end of the rod 19. Said spring is arranged so that there is normally applied a pressure on the rod 19 tending to urge the rod 19 vertically upward in the underreamer, thus providing means normally urging the cutters to the reaming position. 23 indicates a closure screwed into the upper end of the body which encloses the chamber 20 from the flushing fluid admitted down the drill pipe. Said chamber 20 is thus entirely enclosed from contact either with the flushing fluid supplied to the underreamer or with débris or mud found

in the well hole. Said chamber 20 may be and preferably is packed with a lubricant during the operation of the underreamer. To prevent mud clogging in the slot 18 in the blade 3, there is formed an edge 29 at the lower end of said slot which will readily cut or divide mud tending to clog or pack therein.

On opposed sides of the chamber 20 extend flushing ducts 24 which join channels 25 extending longitudinally through the upper riders 10 from which the flushing water is discharged into the space between the cutters 7 and bottom of the ways 6 when the 15 said cutters are in the reaming position to and through a channel 26 in the lower rider 10 and discharged from the bottom end of the cutters 7.

In operation, the cutters 7 are pressed 20 down against the head 17 until the cutters 7 can assume the collapsed or non-reaming position when they are pressed in the body and can be tied by a cord or held by other suitable means in the non-reaming position. 25 The underreamer is then lowered into the well casing and as the reamer enters the well casing the cord is cut. When the reamer is lowered below the well casing the cutters 7 will be released and will be forced upward 30 by the tension in the spring 21 over the rider surface 10 into the reaming position where the cutter edges 15 and 16 extend beyond the body of the reamer and are in position to ream a hole of sufficient size to permit the 35 well casing to be lowered. During the reaming operation the blade 3 and fish-tail cutter edge 4 continually stir and cut up the heavy material dislodged from the sides of the well hole and dropped in front of the underreamer so that flushing fluid sent through 40 the ducts 24 and discharged from below the cutters may carry this material back and out of the well. The blade 3 also serves to guide the underreamer during the reaming 45 operation and thus insures the drilling of a straight hole. To this end, the length of the cutting edge 15 aids, in that through repeated contact with each portion of the formation such cutting edge 15 tends to straighten 50 the well hole. It will be observed that in the reaming position the entire part of both the cutters 7 and the members employed to actuate the cutters are held enclosed by or flush against the body so that there is no 55 space for the accumulation of mud which will prevent the collapse of the cutters. Moreover, the spring 21 is entirely closed off from either the mud or débris encountered in the drilling operation or from the flushing 60 fluid sent down to the underreamer, and thus mud or débris cannot clog in between the parts of the mechanism employed for actuating the cutters. Thus it is found that the underreamer constructed according to this 65 invention can at all times readily be col-

lapsed to the non-reaming position and withdrawn through the well casing.

Another advantage of the underreamer herein described is that when soft formations which tend to cave in are encountered, this underreamer may be employed both for the original drilling of the hole and the reaming operation, and in this way the hole drilled and reamed without danger of a cave-in occurring.

Another advantage of this invention is that the cutters may be made as long as desired and this is accomplished simply by varying the length of the body and cutters. Thus an underreamer is provided which 80 will present a cutting edge to the formation which cutting may be several times greater in length than the diameter of the body.

While the underreamer herein described is well suited for the purpose of this invention, it is not intended to limit the invention to the specific construction or details thereof of forming a part of the preferred embodiment of the invention, but various changes in the details of construction and arrangement of parts may be made without departing from the spirit of the invention. This invention is of the scope set forth in the accompanying claims.

I claim:

1. A rotary well underreamer comprising a body having undercut cutter ways extending longitudinally along and parallel with the axis of the body, spaced rider surfaces parallel with the cutter ways, cutters slidable in said ways and arranged so that in the reaming position the cutters bear on said rider surfaces back of the cutting edges of said cutters with the cutting edges only extending from the ways, and spring means 100 normally urging the cutters to the reaming position.

2. A rotary underreamer comprising a body having undercut cutter ways extending longitudinally along and parallel with the axis of the body, rider surfaces parallel with the cutter ways, elongated cutters slidable in the ways and arranged so that in the reaming position the cutters bear on said rider surfaces back of the cutter surfaces of the cutters with the cutting edges extending from the ways, and spring means normally urging the cutters to the reaming position, and flushing ducts extending through the body.

3. A rotary underreamer comprising a body having undercut cutter ways extending longitudinally along and parallel with the axis of the body, spaced rider surfaces extending parallel with said ways, elongated cutters slidable in the ways and arranged so that in the reaming position the cutters bear on said rider surfaces back of the cutter surfaces of the cutters with the cutting edges extending from the ways, spring means nor-

mally urging the cutters to the reaming position, flushing ducts extending through the body, a spring enclosing chamber in said body, and a closure for the chamber enclosing the chamber from communication with said flushing ducts.

4. A rotary underreamer comprising a body having longitudinal undercut cutter ways extending parallel with the axis of said body, cutters slideable in said ways and having substantially vertical cutting edges of relatively greater length than the reaming diameter of the underreamer, spaced rider surfaces parallel with said ways, the cutters being arranged so that in reaming the cutters bear on said rider surfaces back of the cutting edges with the cutting edges only extending from the ways, and means yieldingly maintaining the cutters in a reaming position.

5. A rotary well underreamer comprising a body having longitudinal undercut cutter ways extending parallel with the axis of said body, cutters mounted within the ways and having cutting edges adapted to extend laterally out from the ways, spaced apart rider surfaces on the confronting surfaces of the cutters and body extending parallel with said ways, means for normally urging the cutters over the rider surfaces to the reaming position, and flushing ducts in the body and communicating with the ways in which the cutters are mounted, thereby to discharge flushing fluid at the lower end of the cutters.

6. In a rotary well underreamer, a body having longitudinal undercut ways extending parallel with the axis of said body, reaming blades slideable in said ways and having elongated substantially vertical cutting edges adapted to extend laterally outward from said ways in the reaming position, spaced apart rider surfaces between the reaming blades and body, extending parallel with said ways, for translating the reamer blades to and from the reaming position up-

on relative longitudinal motion of the reaming blades and body, a head engaging the lower end of such reaming blades, and means yieldingly urging the head into upward position to thereby translate the reamer blades to the reaming position.

7. A rotary underreamer comprising a body having longitudinally undercut cutter ways extending parallel with the axis of said body, cutters slideable in said ways and having elongated, substantially vertical cutting edges adapted to extend laterally from said ways in the reaming position, spaced apart rider surfaces between the reaming blades and body parallel with said ways, for translating the reaming blades to and from the reaming position upon relative longitudinal motion between the reaming blades and body, a head engaging the lower end of such reaming blades, and spring means normally urging the cutters to the reaming position, the cutters being adapted to be collapsed against said spring means by a force exerted thereagainst tending to move the cutters downwardly.

8. A rotary underreamer comprising a body having undercut cutter-ways extending longitudinally along the body and parallel with its axis, spaced rider surfaces in said ways and extending parallel thereto; cutters slideable in said ways and arranged so that in the reaming position the cutters bear on said rider surfaces back of the cutting edges of said cutters with the cutting edges only extending from the ways, the cutting edges being elongated substantially vertically, flushing ducts extending through the body, spring means normally urging the cutters upwardly over the rider surfaces to the reaming position, a spring enclosing chamber in said body, and a closure for said chamber enclosing the chamber from communication with said flushing ducts.

Signed at Los Angeles, California, this 5th day of October, 1923.

MERLIN C. HAZARD.
